UNITED STATES PATENT OFFICE.

GEORGE H. DAY, OF SOUTHBIDGE, MASSACHUSETTS, ASSIGNOR TO AMERICAN
OPTICAL COMPANY, OF SOUTHBIDGE, MASSACHUSETTS, A VOLUNTARY
ASSOCIATION OF MASSACHUSETTS.

TEMPLE.

1,266,223.

Specification of Letters Patent. Patented May 14, 1918.

Application filed September 18, 1917. Serial No. 191,176.

To all whom it may concern:

Be it known that I, GEORGE H. DAY, a citizen of the United States, residing at Southbridge, in the county of Worcester and State of Massachusetts, have invented certain new and useful Improvements in Temples, of which the following is a specification.

This invention relates to improvements in temples or members for retaining ophthalmic mountings on the face, and has particular reference to an improvement in that type of temple in which part is formed from metal and part from shell, zylonite or similar non-metallic material.

The leading object of the present invention is the provision of an improved joint between the said metallic and non-metallic parts which shall firmly and satisfactorily connect said parts.

A further object of the present invention is the provision of an improved manner of uniting the various parts so as to present a neat and attractive structure and to rigidly and firmly unite the parts and prevent any liability of breakage at the joint by reinforcement of the more brittle non-metallic member.

Another object of the present invention is the provision of an improved manner or process of so joining the parts that they will be securely and satisfactorily held and the finished article will be braced or reinforced and also locked against accidental loosening movement, substantially as illustrated.

Other objects and advantages of my improved construction should be readily apparent by reference to the following specification taken in connection with the accompanying drawings, and it will be understood that I may make any modifications in the specific details of construction shown and described within the scope of the appended claims without departing from or exceeding the spirit of my invention.

Figure I represents a side view of one form of my improved temple.

Fig. II represents a similar view of another form thereof.

Fig. III represents a plan view of the construction shown in Fig. II.

Fig. IV represents a fragmentary de-

tail view of the joint end of the side piece of Fig. I enlarged.

Fig. V represents a similar plan view of said part.

Fig. VI represents a longitudinal sectional view as on the line VI—VI of Fig. III.

Fig. VII represents a similar sectional view on the line VII—VII of Fig. II.

Fig. VIII represents a view similar to Fig. VI but illustrating a modified construction.

Fig. IX represents a similar view of another modification.

Fig. X represents a longitudinal sectional view of the construction shown in Fig. IX.

Fig. XI represents a sectional view of another modified form of the construction.

Fig. XII represents a view of a further form of joint.

Fig. XIII represents a sectional view on the line XIII—XIII of Fig. XII.

Fig. XIV represents a view of the ear hook blank.

Fig. XV is a fragmentary sectional view illustrating one of the early steps in the process of forming my improved temple.

Fig. XVI illustrates the position of the parts for the performance of a further step of the process.

Fig. XVII represents a view of this step completed.

Fig. XVIII represents a view of the next succeeding step.

Fig. XIX represents a sectional view of the joint completed.

Fig. XX represents a perspective view of the inclosing cap or ferrule.

Fig. XXI is a view similar to Fig. XVIII of a modified method of carrying out the process.

Fig. XXII is a perspective view of a slightly different form of ferrule to be used in connection with my improved joint.

Figs. XXIII, XXIV, and XXV are elevations illustrating various forms of the completed joint.

Fig. XXVI is an elevation of another form of the joint, and

Fig. XXVII is a longitudinal sectional view of the form shown in Fig. XXVI.

In the drawings, the numeral 1 designates the usual temple side formed of round

wire, while the numeral 2 denotes a corresponding part formed from flattened stock, the wire being provided in either event with one end of the head portion 3 of suitable construction to engage the temple dowel and pivotally connect the side and lenses.

In Fig. I, I have shown the portion 1 as of round stock and in a number of other figures of the drawings as flat stock, it being understood that for purposes of the present invention it is immaterial which type of stock is employed for the main portion of the side.

15 Broadly described the essential features of the present invention and process consist in forming an interlocking joint between the metallic and non-metallic parts and in then surrounding this joint with a cap or ferrule member which shall reinforce the joint and shall tightly bind or hold the parts together.

20 More specifically considered the invention resides in the structure and process by which the metallic and non-metallic parts are interengaged or interlocked one with the other by relative lateral as distinguished from relative longitudinal movement, and in which the cap or ferrule is then slid along to overlie the joint and prevent lateral disengagement of the parts.

25 Referring to the drawings: In Figs. IV and V, I have shown the side portion 1 as flattened into the head 4, cut preferably with the bevel or diagonally extending face 5, from which depend the ear hook engaging teeth 6. It will be understood that these teeth could be otherwise formed on the round wire than by flattening, but I preferably flatten the material in order that it may 40 more readily fit into a suitable slot 7 in the ear hook portion 8. In the case of the form shown in Fig. VI, and in a number of the following views, however, as the side 2 is initially formed from flat stock, it is not necessary to form the head 4 by flattening, but merely to cut or otherwise produce on the head the teeth 6 for biting into the ear hook 8.

30 In the several forms of the invention possessing these teeth, in the preferred operation of my process I preferably form the diagonally extending kerf or slot in the end of the ear hook of approximately the size to receive the head or terminal portion 4 of 55 the metallic side and then by relative lateral shifting of the parts suitably press or force the heat down into the kerf so that the teeth 6 will bite into the material of the ear hook 8.

60 It will, of course, be understood that if preferred notches may be formed in the lower wall of the kerf to receive the teeth so that they may accurately fit together, but for ease of assembling I have found that it 65 is merely necessary to form the kerf and

then relatively forcibly shift the parts, when the teeth will automatically bite into the kerf and securely interlock with the ear hook without the necessity of forming the receiving notches therein.

70 The general manner of assembling the construction shown in Figs. VIII, XII, and XV is the same as that just described.

In the assembling, however, of the form shown in Fig. XI, I preferably spread apart 75 the two fingers 9 there illustrated, slipping the temple end therebetween and subsequently pressing them inward so that they bite into opposite sides of the ear hook, while in the form shown in Figs. IX and X the 80 temple is split or kerfed and the terminus of the side suitably slipped thereinto and the material of the ear hook subsequently pressed inward either under the influence of heat, while the temple end is heated, or cold, 85 and simply through the influence of pressure to cause the material to expand in the bosses 10, interlocking with the aperture 11, to securely lock the parts together.

90 In any event, the parts having been suitably assembled with the head on the end of one interlocking with the material of the other, I slip over the parts the ferrule 12 shown in detail in Fig. XX, and preferably having the rectangular or elongated slot 13 95 fitting the correspondingly shaped portion of the temple so that it is locked against rotation relative to the temple.

99 There are several methods of applying this ferrule to obtain the desired result. The 100 ferrule may either be initially slightly larger than the end of the ear hook or of approximately the size to receive the end of the ear hook as illustrated in Fig. XVIII for example, and may be slipped over the parts 105 and subsequently swaged or reduced down to cause it to become embedded in the material of the ear hook section, thus compressing the material at the joint around the head on the temple side, causing additional 110 rigidity of the parts at this point, and embedding the ferrule onto the ear hook portion to make a substantially flush joint therewith, as indicated in Fig. XIX.

115 As an alternative method I may turn or press a reduced portion on the end of the non-metallic member, either plain to receive the ferrule, and decrease the amount of reduction necessary to firmly connect the parts, or may make a tapered end portion as 120 shown in Fig. XXI, and then force the ferrule thereover to obtain desired tightness of the joint.

125 As an example of a form of my construction in which additional swaging is employed to increase the tightness of the joint and supplement the gripping action of the teeth 6 in preventing separating of the parts by direct pull, I would direct attention to the form illustrated in Figs. VIII to X, 130

XXVI and XXVII, in which the ferrule is formed with a circumscribing exterior groove 14, the material biting down interiorly into the non-metallic ear hook section 5 and forming a sort of head on that section embedded within the tubular end of the ferrule.

Attention is also particularly invited to the construction as illustrated in Figs. VIII, 10 IX, and X, for example, in which it will be noted that in Fig. VIII by formation of the exterior groove at 14 in the ferrule the material of the ferrule is caused to actually bite down into the material of the ear hook 8, while in Fig. VII a corresponding result, though less noticeable, has been accomplished by compressing the ferrule at the rear or open end 15 to a greater degree than at the closed or forward end, so that a long gradually tapering head is provided on the ear hook section 8, said head being largest at its forward end so that it is firmly locked within the ferrule, while at the same time the operation of swaging causes the forward 25 part of the ferrule to firmly bite into and frictionally and mechanically interlock with the side to prevent forward movement of the side relative to the ferrule, the ferrule thus having a locking engagement with both 30 the side 2 and the ear hook 8 independent of their interlocking laterally opening joint, whereby the grip of the ferrule on the two parts when properly assembled is sufficient to hold the parts together if necessary independently of the joint aforesaid.

It will also be noted that the surrounding ferrule bears against the head of the metallic side, preferably at diametrically opposite points and locks it against any bending movement relative to the non-metallic portion, tending to cause a breaking or working loose of the joint, while the fitting of the flattened head between the walls of the kerf in the end of the ear hook portion prevents 45 absolutely any relative twisting of the parts. If desired the teeth may be of sufficient length as shown in Fig. XII for example to extend entirely through the ear hook at certain points and contact with the ferrule at 50 the opposite side from that on which they are introduced, thus enabling the ferrule to best brace the parts against relative angular bending or breaking of the joint.

In Fig. XXII I have illustrated in perspective a very desirable form of ferrule wherein the body 15 is formed at one end with a tapering portion 16 which incloses the end of the temple side 4 while the body 55 itself entirely incloses the joint. The complete joint as provided by this improved form of ferrule is best illustrated in Fig. XXVI.

In Fig. XXVII I have illustrated that 60 form of the invention wherein the flattened head of the temple side is provided with

an elongated slot 17. In assembling this form of the invention the flattened head 4 of the temple side is inserted into the slot in the end of the ear hook portion, the ferrule is then placed in position over the joint 70 and pressure brought to bear upon the same which will groove the ferrule as shown at 18 forming a beading 19 which bites into the non-metallic material of the ear hook and retains the same against any longitudinal movement with respect to the temple side. The pressure upon the ferrule will also force the material of the ear hook into the elongated slot to assist in retaining the parts against longitudinal movement. It 75 will be noted that the end of the ferrule is pressed firmly into the material of the ear hook to provide a substantially smooth joint. From this it will be apparent that by the use of the ferrule as shown in Figs. XXII, 80 XXVI, and XXVII a joint is provided which not only forms a neat joint but one wherein the parts are securely held against any relative movement since the inter-engagement of the head of the side in the slot of the 85 ear hook prevents relative twisting of the parts, the forcing or swaging of the ferrule around the joint binds the parts tightly together and the engagement of both sides of the head with the ferrule prevents relative binding of the parts at the joint, this 90 compression also forcing the material of the hook into the eye of the head to interlock therewith and prevent relative longitudinal separation of the parts, while such 95 separation is also prevented by the interlocking of the head with the neck of the ferrule and the frictional engagement of the entire ferrule and interlocking of the grooved portion thereof with the ear hook. 105

From the foregoing description taken in connection with the accompanying drawings, the structural features and method or process of constructing my improved combination metallic and non-metallic temple 110 should be readily understood, and it will be seen that I have provided a construction in which the parts have a firm interlocking connection one with the other, and in which one of the parts fits down into the other 115 end in which the joint is reinforced and the several parts securely bound and pressed together by means surrounding, concealing and holding the joint, which means serve to lock the parts against disengaging movement in the direction of their initial fitting together. 120

It will also be noted that the surrounding ferrule bears against the head of the metallic side, preferably at diametrically opposite 125 points and locks it against any bending movement relative to the non-metallic portion tending to cause a breaking or working loose of the joint, while the fitting of the flattened head between the walls of the kerf in 130

the end of the ear hook portion prevents absolutely any relative twisting of the parts. If desired the teeth may be of sufficient length, as shown in Fig. XII for example, 5 to extend entirely through the ear hook at certain points and contact with the ferrule at the opposite side from that on which they are introduced, thus enabling the ferrule to best brace the parts against relative 10 angular bending or breaking of the joint.

I claim:

1. The combination with an enlarged ear hook member having a laterally opening slot formed therein, of a temple side having a 15 head portion introduced laterally into the slot and interlocking with one wall of the slot, and means for securing the parts in interlocked engagement.

2. The combination with a non-metallic 20 ear hook, of a temple side having a head forced laterally onto the ear hook and a ferrule encircling the joint to prevent lateral disengagement of the parts.

3. The combination with a non-metallic 25 ear hook portion having a kerf formed therein, of a temple side having a head adapted to fit within the kerf and teeth to bite into one wall of the kerf and secure the parts against relative longitudinal movement, and 30 means encircling the joint for retaining the teeth in interlocking engagement with the ear hook.

4. The combination with a kerfed non-metallic ear hook, of a temple side having a 35 head fitting within the kerf projections on one of said parts interlocking with the other of said parts for securing them against relative longitudinal movement, and additional means for securing the parts against lateral 40 disengaging movement.

5. The process of uniting a side and ear hook of a temple for an ophthalmic mounting, consisting in slotting one of said parts to provide a kerf, forming the other of said 45 parts with a flattened portion adapted to fit within the kerf, forming projections on one of the parts to interlock with recesses in the other of said parts, and applying a ferrule around the parts by pressure to compress 50 the joint and secure the parts against disengagement.

6. The combination with an ear hook section having a diagonally extending kerf formed in one end thereof, of a temple side 55 having a head shaped to fit the kerf, one of

said parts having projections interlocking with the other of said parts to lock them against longitudinal separating movement, and a ferrule surrounding the joint and engaging the temple side at both sides of the 60 kerf and tightly embracing the adjacent portion of the ear hook to brace the parts against relative lateral or relative angular bending movement.

7. The combination with an ear hook and 65 a temple side, of a laterally opening joint connecting said parts, and a ferrule forced over the joint to lock the parts against lateral separation.

8. The combination with an ear hook section 70 and a temple side having a laterally opening joint and having interlocking parts preventing relative longitudinal movement of the parts, of means embracing said parts at the joint to prevent lateral separation 75 thereof.

9. The combination with a temple side and an ear hook section, said parts having a laterally opening joint, of means forced 80 around said joint under pressure to insure tight union of the parts and prevent lateral disengagement thereof.

10. The combination with a temple side and ear hook section having a laterally opening interlocking joint, of a ferrule having 85 one end closely fitting one of said parts and the opposite end fitted over and closely engaging the other of said parts, said ferrule being compressed to bite into the inclosed part and hold the joint under compression 90 while preventing lateral disengagement of the parts.

11. The combination with a temple side and ear hook section having a laterally opening joint, of a ferrule fitting over the joint 95 and compressed thereonto to bite into and be partially embedded in one of the parts at the joint.

12. The combination with a kerfed non-metallic ear hook, of a temple side having 100 a head fitting within the kerf, projections on one of said parts interlocking with the other said parts for securing them against relative longitudinal movement.

In testimony whereof I have affixed my 105 signature, in presence of two witnesses.

GEORGE H. DAY.
